O. J. PARKS

MANUFACTURE OF EDGE WELDED STRUCTURES

Filed Mar. 25, 1920

Patented Mar. 13, 1923.

1,448,416

UNITED STATES PATENT OFFICE.

OSTRANGER J. PARKS, OF RIVER FOREST, ILLINOIS, ASSIGNOR TO GENERAL AMERICAN TANK CAR CORPORATION, OF CHICAGO, ILLINOIS, A CORPORATION OF WEST VIRGINIA.

MANUFACTURE OF EDGE-WELDED STRUCTURES.

Application filed March 25, 1920. Serial No. 368,724.

To all whom it may concern:

Be it known that I, OSTRANGER J. PARKS, a citizen of the United States, residing at River Forest, in the county of Cook and 5 State of Illinois, have invented a new and useful Improvement in the Manufacture of Edge-Welded Structures, of which the following is a specification.

My invention, generally considered, relates to improvement in the manufacture of edge-welded structures regardless of the particular kind of structure, but more particularly to tank cars having anchorages on the tank portions of the cars co-operating 10 with the under-frames of the cars to prevent undesirable displacement of the tanks on the under-frames.

Generally stated, my primary object is to augment the rigidity of the connection between elements secured together by edge-welding, and more particularly, and as relating to tank cars, to provide for the edge-welding together of parts thereof, and more especially anchoring means for tanks, in 15 such a way as to cause these parts to resist to the desired degree the stresses to which they are subjected in use, thereby greatly facilitating the manufacture of structures of this character and economizing in their 20 production.

Referring to the accompanying drawing:—

Figure 1 is a broken view in side elevation of the tank portion and an anchor 25 therefor, of a tank car, the anchor portion being secured to the tank in accordance with my invention. Figure 2 is a bottom plan view of one of the elements forming the anchoring means. Figure 3 is an enlarged view in cross-section taken through 30 a portion of the tank and one of the elements of the anchoring means secured thereto; and Figure 4, a broken, cross-sectional, view taken through the tank, the anchoring 35 means, and the underlying center sill of the car.

I have chosen to illustrate my invention in connection with a common form of construction of tank car and which includes 40 the tank portion 5 surmounting the under-frame of the car, the center sill of which is represented at 6, this sill being illustrated as formed of a pair of structural iron beams 45

7 spaced apart with their flanges 8 and 9 turned outwardly and having a bottom 55 plate 10 and a top plate 11 secured thereto and forming a box-like structure. The anchorage means for the tank, in accordance with common practice, are provided at opposite ends of the tank, one only of these 60 means being shown and each comprising a pair of members 12 of steel, in the form of plates having the portions 13 flatwise opposing, and secured to, the under side of the tank 5 and at which the tank is supported, with the lower edges of the plates 65 outwardly turned as shown at 14 at which they bear against the upper surface of the plate 11, the plates 13 being secured to the tank in accordance with my invention, as 70 hereinafter explained. The plates 12 are secured to the sill 6, by bolts 15 which extend through enlarged openings 16 in the flanged portions 14 of the plates 12 and also through openings in the flanges 8 and 75 11 and a bar 16^a superposed on the flanges 14, the structure thus provided while operating to anchor the tank 5 on the under-frame permitting of relative 80 lengthwise movement of these parts under 85 expansion and contraction of the structure.

In accordance with my invention the plates 13 are secured to the under side of the tank 5 in sidewise opposed condition, by welding these parts together along the edges presented by the plates 13. In order that there shall be presented, for the edge-welding together of these parts, the necessary length of edge to firmly hold these 90 parts together and resist the stresses to which they are subjected in use, I aperture the plates 13, as by perforating them, to produce openings therethrough affording the desired length of edge at which the welding is to take place, the aperturing as 95 shown in the drawings, viz., by providing the two relatively long openings 17 in each plate 13, being desirable for a construction of the form and character shown, it being understood that in the welding operation, 100 which may be performed in any desirable way, as is well known, the plates 13 will not only be welded along their outer edges of the tank but also along the edges of the apertures 17 as indicated at 18 in Fig. 3, 105 thereby resulting in the rigid attachment of

the tank to the anchoring means, and by an operation which may be readily, and economically, performed.

While I have illustrated and described a particular manner of utilizing my invention, and have shown it as applied to a particular construction, I do not wish to be understood as intending to limit it thereto as various alterations and modifications may be made without departing from the spirit of my invention, it being my intention to claim my invention as fully and completely as the prior state of the art will permit.

What I claim as new and desire to secure by Letters Patent is:

1. In a tank car, the combination with its tank, of anchorage means therefor involving a member sidewise opposing said tank and apertured to provide an augmented length of edge for welding, said

member being welded to said tank along the edges afforded by said member.

2. In a tank car, the combination with its tank, of anchorage means therefor involving a member sidewise opposing said tank and apertured between its marginal edges to provide an augmented length of edge for welding, said member being welded to said tank along the edges afforded by said member.

3. In a tank car, the combination with its tank, of anchorage means therefor involving a member sidewise opposing said tank and apertured between its marginal edges to provide an augmented length of edge for welding, said member being welded to said tank along the edges afforded by said member, the surface of the tank which is opposed by said apertured member being uninterrupted.

OSTRANDER J. PARKS.
